WINDING MACHINE

Mervin Allatt, Short Hills, N. J., assignor to
 Millie Patent Holding Co., Inc., New York, N. Y.,
 a corporation of New York

Application November 8, 1932, Serial No. 641,704

15 Claims. (Cl. 226—56)

The present invention relates to mechanisms for forming bag-like receptacles for tea, coffee, etc., and embodies, more specifically, an improved device for forming receptacles of the above character having strings and bags attached thereto and winding the string about the necks of the receptacles to shorten the effective length thereof and reduce the tendency of such strings and tags to become entangled with the strings and tags of adjacent receptacles when placed in a common container.

As is now commonly known, the packing of a number of bag-like receptacles having strings and tags secured thereto in a common container frequently results in causing the strings and tags of the several bags to become tangled and thus gives rise to annoyance and inconvenience in removing the individual receptacles from the container as they are to be used. Several forms of bags and tags have been suggested heretofore with an object of avoiding the above difficulty, but the manufacture of such suggested forms has not as yet been accomplished satisfactorily. In accordance with the present invention, it is proposed to wind the string of a receptacle about the neck thereof, thus shortening the effective length of the string and placing the tag at the end thereof into close proximity with the bag. As a result, the tendency of the strings and tags of the several bags to become tangled is reduced and the present invention provides a machine by means of which the strings of the bags are conveniently wound about the respective bags.

An object of the invention, accordingly, is to provide a machine by means of which the strings of bag-like receptacles are wound about the necks thereof to position the tags at the ends of the strings adjacent the respective bags.

A further object of the invention is to provide a mechanism by means of which a bag is taken from a bag closing mechanism and rotated about an axis passing through the neck thereof, the string and tag secured to the neck of the bag being held frictionally whereby the rotation of the bag effects the winding of the string about the neck thereof in an effective fashion.

A further object of the invention is to provide a winding mechanism for bag-like receptacles wherein means is provided for grasping a bag about its neck and rotating the same upon the axis of the neck, a frictional guide being provided for accurately directing the movement of the string and tag during the movement of a bag from a closing position to the winding device.

Further objects, not specifically enumerated above, will be apparent as the invention is described in greater detail in connection with the accompanying drawings, wherein:

Figure 1 is a plan view showing a bag closing and winding mechanism constructed in accordance with the present invention. 5

Figure 2 is a view in front elevation showing a bag-like receptacle formed in accordance with the present invention. 10

Figure 3 is a view in section, taken on line 3—3 of Figure 1, and looking in the direction of the arrows. 15

Figure 4 is a detail plan view showing the position of the bag transfer arm after having been moved into such position that the bag is grasped by the winding mechanism. 20

Figure 5 is a view in section, taken on line 5—5 of Figure 4, and looking in the direction of the arrows, this view showing the bag grasping and winding mechanism in larger scale. 25

Figure 6 is a view in front elevation, showing the bag winding device and operating mechanism thereof. 30

Figure 7 is a view in transverse section taken through the frictional tag guiding mechanism of the present invention. 35

Figure 8 is a plan view of the friction shoes and guides of Figure 7. 40

Figure 9 is a view in section, taken on line 9—9 of Figure 8 and looking in the direction of the arrows, showing the elements in larger scale. 45

Figure 10 is a plan view of the operating mechanism for the elements shown in Figure 1. 50

Figure 11 is a view in front elevation showing the elements of Figure 10. 55

With reference to the above drawings, bag-like receptacles are received in radial arms 20 mounted upon a rotatable carrier 21, notches 22 being formed in the ends of arms 20 to receive the receptacles. Member 21 is rotated in a step by step fashion through 90° stages in the construction shown in Figure 1 to bring each arm in succession to a position as indicated by the lower arm 23 in Figure 1. During such movement, the closing of the receptacle may be effected by means of a device indicated at 24 and of common and well known construction as illustrated in the patent to Allatt No. 1,518,551. The closing device 24, as in common practice, comprises a means for inserting a clamp about the neck of the receptacle within the notches 22, at the same time securing a string under the clamp. The free end of the string is provided with a tag and the resulting receptacle is shown in Figure 55

2, the receptacle being indicated at 25, the clamp at 26, the string at 27 and the tag at 28.

When an arm 20 reaches the position of arm 23 in Figure 1, the receptacle carried thereby is removed by means of an arm 29 which is secured to an arm 30, journaled at 31. Arm 30 is actuated by a link 102 which is pivoted eccentrically thereto at 103 and at 104 to disc 105 which is rotated by a power shaft 84. The free end of arm 29 is provided with a fork 32 having bifurcated extremities 33. When the arm 29 swings in a counterclockwise direction, as viewed in Figure 1, the bifurcations 33 engage the bag 25 which is held within the notch in arm 23 and move the bag into the jaws of a transfer arm 34.

Transfer arm 34 is secured to a rock shaft 35 and is formed with bifurcations 36 and 37 upon the end thereof. Bifurcation 36 is formed with an offset, reversely extending jaw 38 having spaced ribs 39 between which the ring 26 of a receptacle is adapted to be received. Bifurcation 37 has a movable jaw 40 journaled thereon at 41, a spring 42 normally urging the jaw toward the jaw 38, being stopped in the position shown in Figure 1 by means of a stop 43. Movable jaw 40 is provided with spaced ribs 39 in a manner similar to jaw 38 and the neck of the bag is thus effectively received between these movable jaws. After a bag is received between the jaws 38 and 40, the transfer arm 34 swings about the axis of shaft 35 and moves the bag into the position shown in Figure 4, wherein it is engaged by a rotating mechanism.

35 The mechanism for rotating the bag is illustrated in Figures 5 and 6, wherein a vertical standard of the machine is shown at 44 upon which a vertical shaft 45 is journaled for rotation. Shaft 45 is journaled in brackets 47 and 48 and, at the lower extremity thereof, is provided with movable jaws 49, journaled upon shafts 50 and formed with interengaging teeth 51. A spring 52 normally urges the jaws into engagement and dogs 53, formed on the jaws, are adapted to be engaged by a plate 54 to facilitate the movement of the jaws into a released position. Plate 54 is mounted upon an axially movable shaft 55, the plate being provided with a guide 56 which slides between pins 57 upon bracket 48. In the position shown in Figure 5, one of the dogs 53 is engaged by plate 54 and the jaws 49 are separated. In the position shown in Figure 6, however, the plate 54 is shown in a lowered position and the jaws are shown as engaging the neck of a bag-like receptacle which has been moved into engaging position.

As the plate 54 descends to permit the jaws 49 to engage the neck of a bag, the movable jaw 40 is moved away from the jaw 38 by means of a cam 58 which is engaged by a roller 59 angularly journaled upon a shaft 60 which is mounted upon an angular extension 61 of the plate 54. In this fashion, interference between jaws 49 and 38 and 40 is avoided.

65 As the bags are moved from the position occupied while being held by the arms 20 in the position 23, the strings and tags secured thereto are guided by means of a guide rail 62 which may extend partially around the carrier 21 and outwardly to a plate 63. A cooperating plate 64 is spaced from plate 63 to form a guide groove 65 through which the strings of the bags pass. Below the rail 62 and plate 63 is a curved guide plate 66 against which the tags move and over which the tags are guided into a position wherein they

lie beneath the plates 63 and 64. Guide 66 terminates in a widened groove 67 into which the tags move, continued movement thereof causing the tags to move over a leaf spring 68 which urges the same upwardly against the bottom surfaces of plates 63 and 64. Continued movement of the tags, as the strings to which they are secured pass through groove 65, brings them under longitudinal rails 69, carried by a plate 70 which is mounted upon an arm 71. The rails 69 constitute friction shoes which serve to force the tags upwardly and maintain the same against the bottom surfaces of plates 63 and 64, the rails being mounted upon leaf springs 72 which are anchored at 74 upon the plate 70. The ends of leaf springs 72 bear upon heads 75 which are formed upon guide rods 73, upon the ends of which the shoes 69 are mounted. In this fashion, the tags are held frictionally during the winding operation to insure the satisfactory winding of the string about the necks of the bags.

Transfer arm 34 and rock shaft 35 are actuated by an arm 76 which is connected to a link 77, pivoted to the end of a lever 78 at 79. Lever 78 is journaled upon a shaft 80 and formed with a crank arm 81 upon the end of which a roller 82 is journaled. Roller 82 is adapted to engage a cam 83 which is mounted upon a power shaft 84 and the cam is so formed as to cause the correct periodic swinging of arm 34.

The plate 70 and arms 71 are actuated by a shaft 85 upon which an arm 86 is mounted. Arm 86 is actuated by an arm 87 connected thereto, being formed upon a link 88 which is connected at 89 to an arm 90 which is journaled upon shaft 80 at 91. Secured to arm 90 is a second arm 92 upon the end of which a roller 93 is journaled to engage the periphery of a cam 94 which is secured to power shaft 84. Reciprocating motion is thus imparted to link 88 to swing the plate 70 from the position shown in the solid lines of Figure 7 to the position shown in dotted lines therein. Link 88 is also connected through a universal connection 95 to an arm 96 which is journaled at 97 upon a stationary portion of the machine. Intermediate the ends of arm 96, a link 98 is journaled at 99. The free end of link 98 is pivoted at 100 to a bracket 101 which is formed upon plate 54. In this fashion, link 88 serves as a means to raise and lower plate 54 periodically.

In order that rollers 82 and 93 may be maintained against the respective cams 83 and 94, springs 106 and 107, respectively, are provided, these springs serving to maintain the elements actuated by the respective arms 78 and 90 in a normal position.

Pulley 46 and shaft 45 with the bag engaging jaws 49 are rotated by means of a belt 108 which is driven from a pulley 109, mounted upon a shaft 110 which is journaled in brackets 111, carried by the frame of the machine. A second pulley 112 is secured to shaft 110 and is driven by a belt 113 which is mounted over a pulley 114 which is secured to the power shaft 84. In this fashion, belt 108 is continuously driven and shaft 45 rotated continuously except when the rotation is interrupted by means of a stop 115 which is secured to the shaft. Stop 115 is formed with oppositely extending arms 116 which are adapted to be engaged by a dog 117, mounted upon an arm 118. Arm 118 is journaled at 119 and actuated by a link 120 which is connected at 121 to a lever 122 which is

5 journaled upon shaft 80 and upon which an arm 123 is mounted. Arm 123 is provided with a roller 124 which is adapted to engage a cam 125 driven by the power shaft 84 and, in this fashion, stop 117 is moved into the path of arms 115 to stop rotation of the shaft 45 when the stop members 49 are in a plane parallel to the planes of the jaws 38 and 40. In this position, the jaws 149 may swing downwardly between 10 the jaws 38 and 40 and engage the neck of the bag, the position of which is indicated by the dotted lines in Figure 5. During this operation the belt slips over pulley 46.

15 The operation of the mechanism described hereinabove will be seen to take place in accordance with the proper spacing and formation of the cams 83, 94 and 125, together with the driving pulley 114. When the arm 20 is in the position shown at 23, the arm 29 is actuated to move the 20 neck of a bag between jaws 38 and 40. The transfer arm 34 is then swung into the position shown in Figure 4 and the bag is placed beneath shaft 45. Plate 54 is lowered and roller 59 cams against the cam 58 to separate the jaws 38 and 40, 25 jaws 49 simultaneously swinging together to engage the neck of the bag, as shown in Figure 6. Stop 117 is then withdrawn from the path of arms 115 and the shaft 45 is permitted to be rotated by the belt 108. During the movement of 30 the bag on the transfer arm, the string and tag secured to the bag are guided by means of rails 62 in guide members 63, the string passing through the slot 65. When the bag is rotated, the tag is drawn through the guide member and between 35 the friction shoes 69 and the lower surface of the guide plates 63 and 64. After rotation of the bag a sufficient amount, the stop 117 swings into the path of arms 115 and the rotation ceases. Plate 54 is then elevated to disengage the jaws 49 and 40 the bag with the string wound about the neck thereof is dropped into a suitable receptacle. The operation of the machine continues to pass through cycles as outlined above.

45 While the invention has been described with specific reference to the accompanying drawings, it is not to be limited, save as defined in the appended claims.

I claim as my invention:

1. Means for shortening the effective length of 50 a string secured to a bag-like receptacle comprising a rotatable member, positive means movable into the path of the rotatable member to stop the member, arms mounted on the member to engage a receptacle, means to move a receptacle to the 55 rotatable member, means to actuate the stop means, and means to open and close the arms while the stop means is actuated.

2. Means for shortening the effective length of 55 a string secured to a bag-like receptacle comprising a rotatable shaft, arms journaled on the shaft and normally urged together to engage a receptacle, an arm on the shaft, and means movable into the path of movement of the arm to engage the last named arm to stop, positively, rotation of 60 the shaft.

3. Means for shortening the effective length of 65 a string secured to a bag-like receptacle comprising a rotatable shaft, arms journaled on the shaft and normally urged together to engage a receptacle, an extension on one of the arms, means to engage the extension, an arm on the shaft, and means to engage the last named arm to stop rotation of the shaft.

4. Means for shortening the effective length of 70 a string secured to a bag-like receptacle comprising

ing a rotatable shaft, receptacle engaging means on the shaft, means for moving a receptacle to the shaft, means on the last named means for releasably engaging a receptacle, means to stop the rotation of the shaft, and common means to release the last named engaging means and actuate the first engaging means.

5. Means for shortening the effective length of 10 a string secured to a bag-like receptacle comprising a rotatable shaft, receptacle engaging means on the shaft, means for moving a receptacle to the shaft, means on the last named means for releasably engaging a receptacle, and common means to release the last named engaging means and actuate the first engaging means.

15 6. Means for shortening the effective length of 20 a string secured to a bag-like receptacle comprising a rotatable shaft, receptacle engaging arms on the shaft, means for moving a receptacle to the shaft, means on the last named means for releasably engaging a receptacle, and a plate movable axially of the shaft to actuate the arms and the last named engaging means.

25 7. Means for shortening the effective length of 30 a string secured to a bag-like receptacle comprising a rotatable shaft, receptacle engaging means on the shaft, means for moving a receptacle to the shaft, means on the last named means for releasably engaging a receptacle, means to stop the rotation of the shaft, and common means to release the last named engaging means and actuate the first engaging means.

35 8. Means for shortening the effective length of 40 a string secured to a bag-like receptacle comprising a rotatable shaft, receptacle engaging arms on the shaft, means for moving a receptacle to the shaft, receptacle engaging jaws on the last named means, one of the jaws being movable with respect to the other, an arm engaging member to actuate the arms, a cam on one of the jaws, and means on the arm engaging member to engage the cam.

45 9. Means for shortening the effective length of 50 a string secured to a bag-like receptacle comprising a rotatable shaft, receptacle engaging arms on the shaft, a transfer arm having a bifurcated extension, receptacle engaging jaws on the extension, one of the jaws being pivoted and urged toward the other jaw, an extension on the pivoted jaw having a cam formed thereon, a plate movable axially of the shaft to engage the first arms, and a roller on the plate to engage the cam.

55 10. Means for shortening the effective length of 60 a string secured to a bag-like receptacle comprising a rotatable shaft, receptacle engaging arms on the shaft, a transfer arm having a bifurcated extension, receptacle engaging jaws on the extension, one of the jaws being pivoted and urged toward the other jaw, an extension on the pivoted jaw having a cam formed thereon, said arms and jaws having grooves formed therein to receive the neck of a receptacle, a plate movable axially of the shaft to engage the first arms, and a roller on the plate to engage the cam.

65 11. Means for shortening the effective length of 70 a string secured to a bag-like receptacle comprising a rotatable shaft, receptacle engaging arms on the shaft, a transfer arm having a bifurcated extension having portions offset with respect to the plane of the arm, receptacle engaging jaws on the offset portions of the extension, one of the jaws being pivoted and urged toward the other jaw, an extension on the pivoted jaw

having a cam formed thereon, a plate movable axially of the shaft to engage the first arms, and a roller on the plate to engage the cam.

12. In combination with means for moving a receptacle to a device for rotating the same and effecting the rotation thereof, means to guide a string secured to the receptacle during movement of the receptacle to the rotating means, and separate means in communication with the guiding means to resist motion of the string toward the rotating means.

13. In combination with means for moving a receptacle to a device for rotating the same and effecting the rotation thereof, means to guide a string secured to the receptacle during movement of the receptacle to the rotating means, and friction shoes communicating with the guiding means to resist motion of the string toward the rotating means.

14. In combination with means for moving a receptacle to a device for rotating the same and

effecting the rotation thereof, a rail to guide a string secured to the receptacle during movement of the receptacle to the rotating means, a plate formed with a groove through which the string moves, and friction members under the plate and spaced upon opposite sides of the groove, whereby a tag on the string will be urged against the underside of the plate.

15. In combination with means for moving a receptacle to a device for rotating the same and effecting the rotation thereof, a rail to guide a string secured to the receptacle during movement of the receptacle to the rotating means, a plate formed with a groove through which the string moves, friction members under the plate and spaced upon opposite sides of the groove, a plate movable toward and away from the first plate, and means to mount the friction members yielding upon the last named plate.

MERVIN ALLATT.
